UNITED STATES PATENT OFFICE.

ATHELSTAN O. JONES, OF ST. LOUIS, MISSOURI.

DEVICE FOR HANDLING BRICKS.

No. 891,548.

Specification of Letters Patent.

Patented June 23, 1908.

Application filed April 6, 1908. Serial No. 425,390.

To all whom it may concern:

Be it known that I, ATHELSTAN O. JONES, a citizen of the United States, and a resident of the city of St. Louis and State of Missouri, have invented a new and useful Improvement in Devices for Handling Bricks, of which the following is a specification.

My invention relates to a device for handling bricks and has for its principal object 10 to avoid the repeated rehandling of the green brick; to provide means whereby stacks of brick built up at the press may be shifted bodily to the kiln, and to attain other advantages hereinafter appearing.

15 The invention consists principally in providing a lift with clamping members arranged to enter between the spaced bricks of the lowermost tier of a stack and to clamp the bricks of said tier with sufficient force to support the weight of the entire stack.

It consists particularly in arranging the clamping device so as to be operated automatically by the hoisting mechanism.

It also consists in the arrangements and 25 combinations of parts hereinafter described and claimed.

In the accompanying drawings, which form part of this specification and wherein like symbols refer to like parts wherever they 30 occur, Figure 1 is a front elevation of a lift embodying my invention in operative relation to the partially completed stack of brick; Fig. 2 is a vertical sectional view of my device on the line 2—2 of Fig. 1, showing 35 it in operative relation to a completed stack of brick; Fig. 3 is a vertical sectional detail view of the uppermost portion of my lift; Fig. 4 is a horizontal section on the line 4—4 of Fig. 2.

40 The frame of my device comprises an elongated horizontal member 1 whose ends 2 are turned laterally at right angles to the body portion, so as to constitute a stiff yoke. Said frame also comprises a channel or rigid 45 vertical member 3 secured to the middle portion of the lower horizontal member and having its upper end 4 turned laterally on the same side as the ends of the horizontal member.

50 Mounted on the horizontal member of yoke are a plurality of equidistant plates 5 arranged to stand vertically edgewise. These plates are spaced from each other and from the ends of the yoke a distance greater than 55 the thickness of a brick A. Preferably, these plates are fixed to the body of the yoke

by rivets extending through the ends of the plates, which plates are bent or flanged for the purpose. By this arrangement, the plates are securely fastened to the yoke and have only such slight movement relative to each other as their resiliency will permit. On the outer face of each of these plates are a plurality of wedge blocks or lugs 6 whose projecting surfaces are inclined or tapered 65 towards the ground.

Between each end of the yoke and the plate adjacent thereto and between each two adjacent plates is a vertically movable plate 7 which is provided on one side with a 70 plurality of wedge blocks or beveled lugs 8 in position to coöperate with the counterpart wedge blocks or lugs 6 mounted on the fixed spacing plates. Each of these vertically movable plates has an upwardly projecting 75 strip 9 fixed flatwise to its rear end, and the upper end of each of these strips is twisted to lie flatwise against a horizontal cross head or member 10 to which all of said strips are riveted or otherwise fastened. This cross 80 member is mounted in a strap 11 provided therefor on the vertical member 3 of the main frame. This strap constitutes a positioning guide for maintaining the movable members in proper position with respect to 85 their fixed counterparts. The resiliency of the flat strips to which the movable plates are secured tends to press such movable plates towards the fixed spacing plates to which they are respectively adjacent. Normally, the 90 movable plates are in their lowermost positions, with only the narrower portions of their wedge blocks in engagement; and, consequently, each movable plate is closer to its 95 companion fixed plate than in its raised position in which the wider portions of the wedge blocks are in engagement.

The cross head 10 has an upwardly extending bail 12 fixed thereto and the upper end of this bail is pivotally secured to a lever 100 13 which is pivoted at the front portion of the laterally projecting end 4 of the upright member of the frame. Journaled on the frame 3 above the lever is a hand lever or cam 14 whose short end is arranged to bear 105 against the upper surface of said lever and thereby lower said lever and the parts connected thereto. Between the fulcrum of the lever 13 and the point of attachment of the vertically movable frame, that is, above the 110 center of gravity of the device, the lever is provided with a bail 15 or other device

adapted for connection with a grab hook or other hoisting mechanism.

The operation of my device is as follows: As the bricks are delivered from the press, they are stacked up in single rows one brick deep just as they are intended to stand in the kiln. The bricks of the lowermost tier or tiers are accurately spaced apart, preferably by the use of marks provided thereon on the floor. The lift, which is preferably hung on a derrick or other suitable hoisting mechanism is then brought into engagement with the stack by entering its pairs of plates in the respective spaces between adjacent bricks. Prior to the operation of entering said plates into the spaces, the hand cam 14 is turned so as to bear the lever and the parts connected thereto downwardly with respect to the main frame, and thereby permit the resiliency of the strips to press the movable plates as closely as practicable to their companion plates that are fixed on the frame. When the plates are properly entered between the bricks, the hand cam is manually turned out of engagement with the lever 13 and the hoisting mechanism set in motion to raise the device. The lifting force is applied from the bail to the lever and thence to the movable frame and the parts connected thereto. Preferably, the initial clamping action is effected by raising the end of the lever 13 manually, instead of depending upon the hoisting mechanism. As the movable clamping plates move upwardly, their wedge members coöperate with the counterpart respective wedge members of the fixed plates and spread said plates apart, that is, the coöperating wedges force the movable plates laterally against the bricks of the lowermost tier or tiers, as the case may be, this lateral movement being permitted by the resiliency of the strips on which the movable plates are mounted. In consequence of this lateral movement of the movable plates, the bricks of the lowermost tier or tiers are firmly clamped between a movable plate and a fixed plate or between a movable plate and an end of the yoke. After the plates have firmly clamped the several bricks of the lowermost tier or tiers, there can be no further movement of the movable members with respect to the frame, and consequently the further application of the lifting force is transmitted to the main frame, and the entire device with the stack of bricks thereon is lifted bodily and transferred to the kiln or other desired place. It is noted that during this operation, the entire weight of the stack is utilized in the clamping action. When the stack is set down at its destination, the lift is disengaged therefrom simply by lowering the lever, which leaves the plates to be withdrawn laterally from the stack.

Obviously, the construction hereinbefore described admits of considerable variation

without departing from my invention, and I do not wish to be restricted to the particular construction shown and described.

What I claim is:

1. A device for handling bricks comprising a frame having a plurality of spaced pairs of members adapted to be inserted between adjacent bricks of a stack, and means for spreading apart said members to clamp said bricks. 75

2. A device for handling bricks comprising a frame having a plurality of spaced parallel members at its lower end, clamping members movably mounted adjacent to said first mentioned members respectively, and means located between each alternate space for spreading apart the members at the sides of said space. 80

3. A device for handling bricks comprising a frame having a plurality of spaced plates fixedly mounted at its lower end, a set of movable plates located between said first mentioned plates, and means between each fixed plate and the movable plate adjacent thereto on one side for spreading the same apart. 85 90

4. A device for handling bricks comprising a frame having a plurality of spaced plates fixedly mounted at its lower end and a plurality of movable plates paired therewith, one side of each plate having wedge members 95 thereon arranged to coöperate with counterpart wedge members on the next adjacent plate.

5. A device for handling bricks comprising a frame having a yoke at its lower end, a plurality of spaced plates in said yoke and a vertical member fixed to said yoke, a second frame movably connected to said first mentioned frame and having a series of plates paired with said first mentioned plates, and means for spreading apart the plates of a pair. 100 105

6. A device for handling brick comprising a rigid yoke having a plurality of spaced plates between the ends thereof and a vertical member fixed to said yoke and having its upper end projecting laterally above said plates, a second frame having plates adjacent to said first mentioned plates, and a lever pivoted to the upper end of the first mentioned frame and connected to said second frame, adjacent plates of the respective frames having counterpart spreading devices thereon. 110 115

7. A device for handling bricks comprising a frame having a yoke at its lower end, a plurality of spaced plates in said yoke and a vertical member whose upper end projects over said yoke, a second frame having a series of plates paired with said first mentioned plates, means for spreading apart the plates of a pair, a lever mounted on the upper end of said first mentioned frame, and means for connecting said second frame to said lever. 120 125

8. A device for handling bricks comprising

a frame having a yoke at its lower end, a plurality of spaced plates in said yoke and a vertical member whose upper end projects over said yoke, a second frame having a series of 5 plates paired with said first-mentioned plates, means for spreading apart the plates of a pair, a lever mounted on the upper end of said first mentioned frame, means for connecting said second frame to said lever, and 10 means for connecting said lever to a hoisting device.

9. A device for handling bricks comprising a frame having a yoke at its lower end, a plurality of spaced plates in said yoke and a vertical member whose upper end projects over 15 said yoke, a second frame having a series of plates paired with respect to said first mentioned plates, counterpart wedge blocks mounted on the adjacent surfaces of plates 20 of each pair, a lever mounted on the upper end of said first mentioned frame and connected to said second frame; and means located between such point of connection and the fulcrum of the lever for securing said 25 lever to a hoisting device.

10. A device for handling bricks comprising a frame having a yoke at its lower end, a plurality of spaced plates in said yoke, and a vertical member whose upper end projects

over said yoke, a second frame comprising a 30 horizontal cross member above said yoke, a series of plates paired with said first mentioned plates and resiliently connected to said cross member, and means for raising said cross member relative to the first mentioned 35 frame, adjacent faces of the plates of each pair being provided with counterpart wedge blocks adapted to spread said plates apart.

11. A device for handling bricks comprising a rigid yoke having a plurality of spaced 40 plates between the ends thereof and a vertical member whose upper end projects above said yoke, a second frame having plates paired with said first mentioned plates, a lever pivoted to the upper end of the first 45 mentioned frame and connected to said second frame, and a hand actuated cam mounted on the upper part of said first mentioned frame and adapted to bear downwardly 50 against said lever, the members of each pair of plates having counterpart wedge blocks on adjacent faces arranged to spread said members apart.
